(57) **CLAIM**

The ornamental design for a graphical user interface for operating panel, as shown and described.

DESCRIPTION

The file of this patent contains at least one drawing executed in color. Copies of this patent with color drawings will be provided by the Office upon request and payment of the necessary fee.

FIG. 1 is a front view of a graphical user interface for operating panel in a first position, showing my new design; FIG. 2 is a rear view thereof; FIG. 3 is a top view thereof; FIG. 4 is a bottom view thereof; FIG. 5 is a right-side view thereof; FIG. 6 is a left-side view thereof; FIG. 7 is another front view thereof in a second position; FIG. 8 is another front view thereof in a third position; FIG. 9 is another front view thereof in a fourth position; and, FIG. 10 is another front view thereof in a fifth position. The broken lines show portions of a graphical user interface for operating panel which form no part of the claimed design.

Images in FIGS. 1-10 include transitions from one setting to different settings. The process in which one image transitions to another image forms no part of the claimed design.

1 Claim, 9 Drawing Sheets
